BLAIR A. ROSS, OF MEMPHIS, TENNESSEE

MEANS AND METHOD FOR PLACING REVETMENT MATS

Application filed August 7, 1930. Serial No. 473,728.

This invention relates to improvements in means and methods for laying mats for the purpose of preventing erosion of the banks or channels, of streams which flow through alluvial or other readily erodable land, or of other bodies of water. Streams flowing through lands of this kind are constantly shifting and if they are to be stabilized, it becomes necessary to revet portions of the bank, often for considerable distances along the stream, such revetment often extending into quite deep water and also well up along the bank. A very considerable portion of this work must be placed under water and other parts above the water. Since there is a considerable fluctuation ordinarily in such streams, advantage may be taken of a higher than average stage to extend the mat so far up the bank, that on a subsequent lower stage one edge will be out of water and such additional work as is necessary may be completed by land methods. It will be understood that this invention relates to that portion of the work which is done under water.

Mats for this work have long been used and many of the types are well known, such for instance as the continuous mat woven of small willow trees and weighted down with rock; or certain forms of concrete slabs tied together by cables or otherwise as may be desired. A form of slab with which this method is particularly available is shown in my pending application for patent Serial Number 473,727, filed Aug. 7th, 1930, to the placing of which form of slab the present drawings are directed.

In under water revetment work, the mat is gotten ready above water and subsequently placed. This is usually done by providing barges with transversely inclined decks having an over-all length when placed end to end somewhat greater than one dimension of the proposed mat; mooring these barges adjacent the beginning point of the work, building or assembling the mat on the inclined deck of these barges, sliding the mat so built over the barge edge, and progressively adding additional portions as the barges move away from the beginning point.

Where small trees such as willow saplings

are used, the trees are laid lengthwise and crosswise and tied together to form a mat of the desired width, the upper end of this mat is anchored by cables, the barges are allowed to slip down stream, or are pulled down stream if necessary, sliding a portion of the mat into the water and leaving room for additional mat to be built, this operation being continued until the desired stretch of bank has been covered.

Such a mat is lighter than water and may be extended to any length desired within the strength of the anchoring cables or of the mat itself. When a section has been completed, the up stream end is weighted until submergence occurs. Thereafter the flow of the current tends to depress the top of the mat gradually forcing it downward as water therebeneath is displaced, permitting barges of rock to be floated over the mat and additional weight to be put thereon to sink it to place. During the weaving of the mat shore cables are necessarily attached at intervals to prevent the mat being swept away from the bank.

Where one form of concrete slabs as now made are used, these slabs are ordinarily made in sections of suitable size at a central mixing plant and are loaded on barges, brought to the site of the work and transferred to the mat launching barges. In such case the barges are ordinarily anchored parallel to the bank, the work being begun either at the bank or the outer edge of the proposed mat as may be desired. The concrete slabs are then secured by fastening them with clips to cables, extending along the blocks and across them, a completed strip of mat is pulled over the edge of the barge and allowed to hang down, supported by one set of the cables. Additional sections are added and secured to the supporting cables and together, forming successive additional strips, and these in turn pulled over the edge of the barge. As the first strip of mat settles to place on the river bottom the barge is moved away from the work and this is kept up until such width as is desired is completed.

In another method successive individual slabs of the mat are slid down parallel cables

to place, an edge of each slab in such case overlying the adjacent edge of a previously laid slab.

The methods above outlined are open to numerous objections. In the case of the willow mat the upper end often becomes waterlogged before the lower end is completed and in such case often becomes unmanageable and cannot be held to its proper place, even in some cases breaking in two. With concrete mats assembled before laying constant trouble is had with breaking in two, or turning the barges over in deep water, since the weight of slab to be supported becomes too great to be properly handled. Both this type and that in which the slabs are slid into place are also subject to the even more serious objection that such extreme flexibility of slab connecting means, must be used to care for the relative angularity of slabs in placing, as to inherently require the use of cables to secure the slabs together.

The objects of this invention are to provide means and methods for laying revetment mats either of small trees, concrete slabs or other material, which will allow laying of large sections of mat without undue stress on slab or other connectors and without undue flexing thereof;

30 To provide means for supporting a mat prior to sinking it to place;

To provide means for releasing the mat portions from the supports therefor, in proper sequence; and

35 To provide means for supporting a mat during and after construction, whereby it may be constructed and removed to a remote site and thereafter be sunk to place.

These objects are accomplished by equipping the usual weaving or assembling barges, with ways extending outward from these barges below water; providing pontons which may be brought over successively completed strips of mat supported on these ways and be secured to such strips to support them as they leave the ways whereby portions of the mat so completed, are supported by pontons until the desired length of mat is completed; and by equipping these pontons with means for automatically releasing the mats supported thereby when excessive load is put on such ponton.

The detailed means by which the foregoing and other objects are accomplished and the manner of their accomplishment will readily be understood from the following specification by reference to the accompanying drawings, are directed to the handling and placing of concrete slabs, and in which:—

60 Fig. 1 is a plan view, on a greatly reduced scale showing individual concrete slabs in place on the launching barge and assembled into a mat with a previous completed part launched and supported by pontons from which the mat is to be lowered.

Fig. 2 is a sectional elevation extending up and down stream showing the beginning of the work with no slabs or part of the mat in place.

Fig. 3 is a similar sectional elevation showing a portion of the mat in place and progression of the placing operation. 70

Fig. 4 is a sectional elevation and transverse to the current of the stream.

Fig. 5 is a plan view, on a larger scale, of 75 one of the pontons showing detail of the attaching means.

Fig. 6 is a side elevation of the same ponton.

Fig. 7 is a sectional end elevation of one 80 of the pontons on a still larger scale showing the action of the automatic release mechanism.

Fig. 8 is a fragmentary sectional plan taken on the line VIII—VIII of Fig. 7.

Fig. 9 is an enlarged fragmentary sectional end elevation of the assembling barge showing the extended ways, and an end elevation of one of the pontons attached to slabs on the ways; and 85

Fig. 10 is a fragmentary end elevation of 90 one of the mooring barges and an end elevation of the adjacent row of pontons with the upstream rows of mat slabs carried thereby.

Referring now to the drawings in which the various parts are indicated by numerals, 95 10 are barges on which the slabs 11 have been placed at the mixing plant and which barges have been towed to the site of the work. 12 are barges which carry cranes or derricks 13 for removing the slabs 11 from the barges 10 and positioning them on launching barges 14, from which launching ways 15 extend. 11A, 11B, 11C, and 11D etc., indicate respectively completed rows of the slabs 11, which have been assembled and connected together on the barge 14 and the ways 15, with alternate rows 11A, 11C, 11E, and 11G, secured to and supported by pontons 16A, 16C etc. Slabs 11I are shown on the ways with the pontons 16I secured thereto just 100 prior to launching. The first row of slabs 11A supported by the row of pontons 16A is anchored at its upstream side by heavy cables 17, which pass under mooring barges 20, and are secured to a second row of mooring barges 21, these latter barges being in turn anchored by cables 22. Cables, preferably omitted to avoid complication of the drawings, extend from the barges 20 to the launching barges 14. The rows of slabs are 105 anchored to the bank by cables 23, secured to deadmen 24, this shore anchorage being provided from time to time as the building of the mat progresses. 25 are release lines for disengaging the mooring cables 17 from 110 the slabs after the mat is sunk to place.

Disposed over the pontons 16 are chains 26 each of which is provided at its ends with hooks 27 one for each end, which hooks are adapted to be engaged with loops 28, or other 115 120 125 130

supporting devices forming part of the mats to be placed. When engaged with a loop each hook is held by a ring 29. 30 are short lengths of chains, each having one end secured to a ring 29 and the other hooked on a support 31 on the ponton.

Each of the chains 26 is secured about midway its length to a cable 32 which cable may be drawn around pulleys 33 into a loop or bight 32A and this bight engaged with a latch 34, which is attached as by a pivot 35 to a float arm 36. 37 is a stop block against which the lower end of the latch 34 may be engaged when the float arm 36 is down. One end of the arm 36 is mounted as on a pivot 38, and the other end carries a float 39.

40 is an eye on the arm 36 with which a line may be engaged to raise the float by hand. 41 is a safety pin.

20 In the type of slab illustrated in my companion application before mentioned, the corners of each of the slabs are cut away to provide a space in which means for securing the slab together may be placed, (Fig. 8).

25 This attaching means comprises a ring 42 and bars 43 each projecting from a slab corner. These bars are first bent upward to receive the ring and after the ring is placed thereover, are further bent over to hold the ring in place. A washer 44 is placed on these bars, the lower end of the loop 28 is passed through this washer, an additional washer 45 is placed under the bars and the loops secured by tightening a nut 46 against the underside of the washer 45. A loop so placed serves as a support for one corner of each of four slabs.

Referring now especially to Figs. 9 and 10 a row of slabs as 11A, were placed on the inclined deck of the launching barge 14, and the corners along the outer edge secured together and to the mooring cables. Additional rows 11B, 11C etc., were then successively assembled adjacent thereto and

45 each row connected at the corners of each slab with the slabs adjacent thereto. After these connections for a row were made the rows of slabs were pulled down the ways to make room for an additional row, this being accomplished by allowing the launching barges and other barges associated therewith to move down stream away from the mooring barge. In accomplishing this each completed row, as indicated by the row 11—I is

50 supported in submerged position by the launching ways 15 as it leaves the barge deck. A row of pontons 161 is assembled over this row of slabs and the chains 26 over these pontons are engaged with the loops 28. At the time of this engagement the chains will be comparatively slack. They

55 are then drawn taut by the cable 32 and the bight of the cable is secured by engaging the latch 34 therewith and also engaging such latch with the block 37. The safety pins 41

are then placed to prevent disaster should any latch be accidentally disengaged. Slack lines 47 are then tied to the eyes 40 and to similar eyes 48 on the adjacent pontons, the lines 47A from the pontons 16A being carried to the mooring barges 20. As soon as all the slabs of this particular row have been engaged with the pontons, the mat thus started is pulled further down the ways, causing the support of the first row of slabs to be transferred from the ways to the pontons. The adjacent row of slabs is also pulled off the ways, the outer edge being supported by the slabs which are ponton supported, and the inner edge by the slabs which are on the ways.

The operation thus described is continued until such length of mat has been built as it is desired to lay. The safety pins at such time are all removed, and the floats 40A on the pontons 16A which lie adjacent the mooring barges 20 are raised by hand, the lines 47A having been provided for such services, the float first raised being either on the ponton furthest away from the bank or nearest to the bank depending largely on the condition of the current but in the majority of the cases being on the ponton furthest from the bank. Raising this first float disengages the latch 34 from the lug 37 and frees the bight 32A of the cable 32 loosening up the chains 26 and permitting the weight of the slabs to pull their ends downward, and the chains to straighten to the position 26A. This drop causes the chains 30 to pull the rings 29 free from the hooks 27, allowing them to disengage from the loops 28, and release these mats.

Ordinarily the additional slab weight transferred to the next ponton in line would so submerge it that its float will automatically trip the latch on the ponton next nearer to the bank, but as this might not occur all the floats on this first row of pontons are preferably raised by hand. When the first row of slabs is released it and the second row secured thereto begin to sink, the action however being retarded by the pull of the mooring cables.

The additional weight of these rows of slabs causes the second row of pontons to submerge so low that the floats carried thereby automatically release the latches on these pontons, and such action automatically continues until the entire mat is released from the pontons. Should any float fail to act the line 47 attached thereto would actuate it. In Fig. 3, the release of the slabs is shown to have progressed as far as the ponton 16X, which have submerged to such point that the float 40X is just ready to release the slabs 16X supported by these pontons.

It will be understood that while the description herein has been confined to the placing of a particular type of concrete-slab mat, it can readily be used in connection

with the willow or other form of wooden mat; with other forms of concrete slab mats; or with other types of mats.

With willow mats the first row of pontons is assembled over the end of the mat, loops being provided on the mat with which the chain hooks may be engaged. Additional rows of pontons are then spaced in identical manner as herein shown and the release of the mat is accomplished identically.

In using this system with willow mats it is possible to weight them very much heavier with stone, before sinking, than is possible where they must be solely supported by their own buoyancy.

With other forms of mats it is only necessary to provide loops to which the chain hooks may be attached and thereafter to follow the same procedure.

This description has been confined to laying a mat down stream adjacent the bank of the river, it will be evident that the same means and methods may be employed in substantially identical manner for laying a mat on any portion of the bottom of the stream whether adjacent the bank or away therefrom.

In many instances it is more convenient to lay mats beginning adjacent the bank and working outward directly into the stream. In such case the end of the mat is anchored to deadmen on the bank and the mooring barges are used to hold the upstream sides of the mat. It is therefore to be distinctly understood that in the claims no distinction is intended between laying a mat down stream along the bank, down stream in the channel, or transversely away from the bank.

It will further be understood that the means and methods herein are equally applicable to work in lakes or other bodies of water.

Having described my invention, what I claim is:

1. The method of building and placing revetment mats, which comprises assembling a mat above water, in successive increments, progressively launching the mat so formed, securing the portion of mat first completed to and supporting same by a series of floats, progressively securing additional portions of such mat as they are completed, to, and supporting same by floats, and on completion of a mat of desired length, releasing the floats along one end of said mat and progressively thereafter releasing additional floats as the previously released portions settle, until all of said floats are released; and allowing said mat to settle to place.

2. The method of building and placing revetment mats, which comprises assembling a mat above water, in successive increments, anchoring the beginning edge of such mat, progressively launching the mat so formed,

securing the portion of mat first completed to and supporting same by a series of floats, progressively securing additional portions of such mat as they are completed, to, and supporting them by floats, and on completion of a mat of desired length, releasing the floats supporting one end of said mat, and progressively releasing additional floats, as the previously released portions settle, until all of said floats are released, and allowing said mat to settle to place.

3. The method of building and placing revetment mats, which comprises assembling a mat above water, in successive increments, progressively launching the mat so formed, securing the portion of mat first completed to and supporting same by a row of floats, progressively securing additional portions of such mat as they are completed, to, and supporting them by, additional rows of floats, and on completion of a mat of desired length, releasing the row of floats along one end of said mat and progressively thereafter releasing additional rows as the previously released portions of mat settle, until all of said floats are released; and allowing said mat to settle to place.

4. The method of building and placing revetment mats, which comprises assembling a mat above water, in successive increments, anchoring the beginning edge of such mat, progressively launching the mat so formed, securing the portion of mat first completed to and supporting the same by a row of floats, progressively securing additional portions of such mat as they are completed, to, and supporting them by, additional rows of floats, and on completion of a mat of desired length, releasing the floats supporting one end of said mat, and progressively releasing additional floats, as the previously released portions settle, until all of said floats are released, and allowing said mat to settle to place.

5. The method of building and placing revetment mats, which comprises assembling a mat above water, in successive increments, progressively launching the mat so formed, securing the portion of mat first completed to and supporting same by a series of floats, progressively securing additional portions of such mat as they are completed, to, and supporting same by floats, and on completion of a mat of desired length, manually releasing the floats along one end of said mat and allowing settlement incident to such release to progressively thereafter release additional floats until all of said floats are released, whereby said mat may settle to place.

6. The method of building and placing revetment mats, which comprises assembling a mat above water, in successive increments, progressively launching the mat so formed, securing the portion of mat first completed to and supporting same by a row of floats, progressively securing additional portions of

- such mat as they are completed, to and supporting same by additional parallel rows of floats, and on completion of a mat of desired length, manually releasing the row of floats 5 along one end of said mat and progressively thereafter allowing settlement of released mat to release additional rows of floats, until all of said floats are released, and allowing said mat to settle to place.
- 10 7. The method of building and placing revetment mats, which comprises assembling a mat, securing the mat to and supporting same by floats, releasing the floats supporting one end of said mat, and progressively releasing additional floats as the previously released portions settle until all of said floats are released, and allowing said mat to settle to place.
- 15 8. The method of building and placing revetment mats, which comprises assembling a mat, securing the mat to and supporting same by a series of rows of floats, releasing the row of floats at one end of said mat and progressively releasing additional rows of floats as the previously released portions settle, until all of said floats are released, and allowing said mat to settle to place.
- 20 9. The method of building and placing revetment mats, which comprises assembling a mat, securing the mat to and supporting same by a series of rows of floats, manually releasing the row of floats at one end of said mat, and allowing settlement of the released portion to progressively release additional rows of floats until all of said floats are released, and said mat to settle to place.
- 25 10. The method of building and placing revetment mats, which comprises assembling a mat, securing the mat to and supporting same by floats, manually releasing the floats, supporting one end of said mat, and allowing settlement incident to such release to progressively release additional floats until all of said floats are released, whereby said mat may settle to place.
- 30 11. The method of building and placing revetment mats, which comprises assembling a mat, securing the mat to and supporting same by a series of rows of floats, manually releasing the row of floats at one end of said mat and allowing settlement of such released end to release the adjacent row of floats, and settlement thereafter to progressively release rows of floats until all of said floats are released, whereby said mat may settle to place.
- 35 12. Means for supporting and releasing a revetment mat having upwardly projecting support loops; said means comprising a plurality of pontons, each equipped with transversely disposed tension members having ends depending along the sides of said pontons, releasable hooks each on an end of a tension member and adapted each for engagement with a mat loop, means on said ponton for taking up slack in said tension members, and holding same, means for releasing said hooks on downward movement thereof, and means for tripping said slack takeup to permit downward movement of said tension member ends and the hooks thereon and release said mat.
- 40 13. Means for supporting and releasing a revetment mat having upwardly projecting support loops; said means comprising a plurality of pontons, each equipped with transversely disposed tension members having ends depending along the sides of said pontons, releasable hooks, each on an end of a tension member and adapted each for engagement with a mat loop, means on said ponton for taking up slack in said tension members, and holding same, means for releasing said hooks on downward movement thereof, and means for tripping said slack takeup to permit downward movement of said tension member ends and the hooks thereon and release said mat.
- 45 14. Means for supporting and releasing a revetment mat having upwardly projecting support loops; said means comprising a plurality of pontons, each equipped with transversely disposed tension members having ends depending along the sides of said pontons, releasable hooks each on an end of a tension member and adapted each for engagement with a mat loop, means on said ponton for taking up slack in said tension members, and holding same, means for releasing said hooks on downward movement thereof, and means for tripping said slack takeup to permit downward movement of said tension member ends and the hooks thereon and release said mat.
- 50 15. In means for supporting and releasing a revetment mat having upwardly projecting support loops; a ponton equipped with transversely disposed tension members having ends depending along the sides of said pontons, releasable hooks each on an end of a tension member and adapted each for engagement with a mat loop, means on said ponton for taking up slack in said tension members, and holding same, means for releasing said hooks on downward movement thereof, and means for tripping said slack takeup to permit downward movement of said tension member ends and the hooks thereon and release said mat.
- 55 16. In means for supporting and releasing a revetment mat having upwardly projecting support loops; a ponton equipped with a plurality of chains disposed transversely across the deck thereof and having ends depending over the opposite sides, hooks, one on each chain end adapted each to engage with a mat loop, latches securing said hooks in engagement with said loops, a cable secured to said chains adapted to take up slack in said chains, an arm transversely disposed across said ponton, a pivotal mounting for

- one end thereof, a float on the opposite end thereof depending down the side of said ponton, a latch carried by said arm for retaining said cable in slack holding position, said latch being releasable on raising said float relative to said ponton manually and by submergence of said ponton, and means secured to said ponton for release of said hook latches on release of slack in said chains.
- 10 17. In means for supporting and releasing a revetment mat having upwardly projecting support loops; a ponton equipped with a plurality of chains disposed transversely across the deck thereof and having ends depending over the sides, hooks one on each chain end adapted to engage with a mat loop, latches securing said hooks in engagement with said loops, means for taking up slack in said chains, and holding same, float controlled means for holding said slack, said means being releasable on raising said float relative to said ponton manually and by submergence of said ponton, and means for releasing of said hook latches on release of slack in said chains.
- 15 18. Means for supporting and releasing a revetment mat having upwardly projecting support loops; said means comprising a plurality of pontoons, each ponton equipped with a plurality of chains disposed transversely across the deck thereof and having ends depending over the sides, releasable means on each chain end adapted to engage with a mat loop, means adapted to take up slack in said chains, and raise said ends, float controlled means for holding such slack taken up, said means being releasable on raising said float relative to said ponton, manually and by submergence of said ponton, and means for releasing said loop engaging means, on release of slack in said chains.
- 20 19. In means for supporting and releasing a revetment mat having upwardly projecting support loops; a ponton equipped with a plurality of chains disposed transversely across the deck thereof and having ends depending over the sides, means on each chain and adapted to engage with a mat loop, means adapted to raise said chains upward, means to hold said chain ends in raised position, means for releasing said loop engaging means on lowering of said chain end, and float controlled means operable manually and by submergence of said ponton, for releasing said chains.
- 25 In testimony whereof I hereunto affix my signature.

BLAIR A. ROSS.
